J. T. NORMAN

COAL FEEDER AND SEPARATOR AND GRADER

Original Filed June 3, 1925

FIG. 2.

FIG. 3.

INVENTOR
Joseph T. Norman
BY
Albert E. Detrich
ATTORNEY

UNITED STATES PATENT OFFICE.

JOSEPH T. NORMAN, OF FREDERICK, MARYLAND.

COAL FEEDER AND SEPARATOR AND GRADER.

Original application filed June 3, 1925, Serial No. 34,707. Divided and this application filed August 27, 1926. Serial No. 131,960.

The invention primarily has for its object to provide a simple and efficient apparatus for feeding coal to a breaker or similar device and for separating and grading it while so feeding it.

In breaking coal it is desired to break it into sizable lumps, as much waste is occasioned by rough treatment resulting in pulverization. It is therefore the purpose of 10 my present invention to provide means for slowly feeding the coal to the breaker in successive steps and for efficiently grading it to the desired size and separating the slate or other undesirable content.

15 Therefore in its more detailed nature the invention seeks to provide a hopper to receive the coal, a table onto which the coal is deposited and which is composed of rotatable rollers, said table being reciprocable, 20 and said hopper stationary and provided with a depending pusher skirt extending down into proximity with the rollers for pushing the coal mass along each time the table moves rearwardly.

25 With the above and other objects in view that will hereinafter appear, the invention still further resides in the novel details of construction, combination and arrangement of parts, all of which will be first fully described, then be particularly pointed out in the appended claims, reference being had to the accompanying drawings, in which:—

Figure 1 is a vertical longitudinal section of the invention.

35 Figure 2 is a plan view.

Figure 3 is a vertical cross section taken on the line 3—3 of Figure 1.

In the drawings, 1 indicates a receiving hopper having a flared receiving throat 40 way and a depending abutment skirt 2 and forwardly extended neck portion 3.

A suitable supporting table or guideway 4 may be provided to serve as a supporting medium for the reciprocable grading and screening table 5 provided with side wings 6 and a receiving floor composed of a plurality of longitudinally positioned spaced rollers 7 mounted in suitable bearings at the ends of the table and to which rotation (in like direction to all rollers) is transmitted through the connections 8 from the pulley connections 9 to which said motion is initially imparted. A suitable pitman 10 is connected to the table, as at 11, and an eccentric 12 with which the pitman has a

strap connection 13, serves to impart reciprocatory motion to the said table 5.

Rotation is imparted to the fixed eccentric shaft through sprocket and chain connection with the pulley shaft and the chain is sufficiently loose or slack to permit the limited reciprocable movement of the power transmitting mechanisms 8 and 9. The same can be said of the belt which drives the pulley 9.

The neck portion 3 with which the hopper is provided may extend substantially to the fore end of the reciprocable table 5 and it will be readily understood that as the coal is fed into the hopper it will deposit down upon the said table and as the forward stroke of reciprocation takes place the said coal will be fed along that table and off its fore or discharge end. The hopper is adapted to be stationarily supported, and the separator table, including the roller rotation imparting mechanism, is reciprocable, hence, each time the table moves forwardly an additional amount of coal will be allowed to fall down upon the same adjacent the abutment skirt 2 and upon the succeeding rearward movement of the said table that skirt will act to force the coal forwardly, thus effecting a step-by-step positive feed of the coal off the fore end of the said table. By reason of the spaced relation of the rollers 7 of the table and the fact that they rotate in like direction the function of that table will be to tend to turn edgewise such flat pieces of coal as are small enough to fall through the spaces between the rollers, thus serving both to grade the coal to the desired size and to screen the same of slate and the like. Also, by rotating all of the rollers in like direction it is impossible for any of the coal lumps to lodge between the same and clog the mechanism.

In practical use the device is preferably positioned to discharge at a low point upon the breaking mechanism in the manner indicated in Figure 1 of the drawings. This overcomes waste by pulverization due to falling of the coal any considerable distance from off the feeder.

This application is a division of my application for Letters Patent filed June 3, 1925, Serial No. 34,707.

From the foregoing description, taken in connection with the accompanying drawings, it is thought that the novel details of

construction, the manner of operation and the advantages of my invention will be readily understood by those skilled in the art.

What I claim is:

- 5 1. In apparatus of the class described, means for separating coal and slate and delivering the coal onto a breaker, said means comprising a longitudinally reciprocating separator table, a hopper located above the table for receiving the coal and delivering it to the separator table by gravity, a transverse fixed abutment above the separator table for holding the coal against movement in one direction while the table is being reciprocated, means for effecting reciprocation of the table, said table including rotating separator rollers between which the slate passes, said rollers being located with their axes lying in the direction of reciprocation, substantially as shown and described.
- 10 2. In apparatus of the class described, means for separating coal and slate and delivering the coal onto a breaker, said means comprising a longitudinally reciprocating separator table, a hopper located above the table for receiving the coal and delivering it to the separator table by gravity, a transverse fixed abutment depending vertically from the hopper into close proximity with the separator table for receiving the coal and delivering it to the separator table by gravity, a transverse fixed abutment depending vertically from the hopper into close proximity with

the separator table and adapted for holding the coal against movement in one direction while the table is being reciprocated, a neck portion extending forwardly from the hopper over and substantially parallel the table to provide a restricted passageway, and means for effecting reciprocation of the table for the purposes described.

- 15 3. In apparatus of the class described, means for separating coal and slate and delivering the coal onto a breaker, said means comprising a longitudinally reciprocating separator table, a hopper located above the table for receiving the coal and delivering it to the separator table by gravity, a transverse fixed abutment depending vertically from the hopper into close proximity with the separator table and adapted for holding the coal against movement in one direction while the table is being reciprocated, said separator table including spaced longitudinal separator elements, and said depending abutment being shaped at its bottom to snugly surround the upper portions of the separator elements and extend a distance therebetween, and means for effecting reciprocation of the table for the purposes described.

JOSEPH T. NORMAN.
